UNITED STATES PATENT OFFICE.

CHARLES JAQUET, OF KÖNIGSHOFEN, STRASSBURG, GERMANY.

WALKING-STICK STOOL.

1,203,118.

Specification of Letters Patent. Patented Oct. 31, 1916.

Application filed June 4, 1913. Serial No. 771,660.

To all whom it may concern:

Be it known that I, CHARLES JAQUET, a subject of the German Emperor, and residing at Königshofen, Strassburg, Alsace, German Empire, have invented certain new and useful Improvements in Walking-Stick Stools, of which the following is a specification.

The present invention relates to an improved portable stool, whose staff is constituted by a hollow walking-stick, adapted to contain an umbrella, or the like, and which carries on its exterior swing supporting-arms, fastened by means which do no obstruct the interior of the stick, said arms ordinarily lying snugly against the latter, but when splayed forming respectively a stool-leg and a seat-support.

Certain embodiments of the invention are illustrated in the accompanying drawings.

Figure 1 is an elevation and Fig. 2 a plan of one form of construction of the new walking-stick stool, and Fig. 3 shows the same folded together. Fig. 4 is a fragmental plan view, illustrating a modified form of the seat. Fig. 5 is an elevation and Fig. 6 a plan of a second form of the improved stool, and Fig. 7 shows the same collapsed.

Referring more particularly to Figs. 1-3, there is slid over the cane, combination umbrella walking-stick, or the like, *a*, a detachable sleeve *b*, to which there is jointed at *k* a support *c*, each limb of which is channelled in such manner that the support can be turned into alinement with the stick *a*, which is then embraced by the same, as shown in Fig. 3. The lower limb of the support *c* constitutes a stool leg, while the upper limb has forged, welded or otherwise attached to its top end lugs *d* for the connection of foldable arms *e*, adapted to support a collapsible triangular seat *f*, indi-

cated by broken lines, and which may be of leather, fabric, or other suitable material. The back corner of the seat is fastened to a ring or collar *l* on the stick *a*. Instead of the arms *e* and seat *f*, a number of arms *g* might be radially disposed with the aid of a collar *h* or the like provided at the top of the support *c*, in place of the lugs *d*, as shown in Fig. 4. The lower ends of the stick *a* and support *c* may be provided with hinged spurs *i*, to prevent the same from sinking into soft ground. When the stool is not in use the whole of the parts may be folded together as shown in Fig. 3, the seat *f* being if desired removed.

In the modification shown in Figs. 5-7 the two integral limbs *c* of the first construction are replaced by two independent limbs *c*¹, each jointed to a detachable sleeve *b*¹ at *k*¹. These two limbs *c*¹ are trough-shaped, so that they may fold compactly against the cane *a*, in similar manner to the limbs *c* of the previous construction. The foldable seat-supporting arms *e* are jointed at *d* to the top end of the upper limb *c*¹.

Having thus described my invention, I claim as new—

A combination stool, cane and umbrella, comprising in combination, a cane, a detachable sleeve adapted to be secured to said cane, a support pivotally secured to said sleeve consisting of two limbs and provided with channels in each of said limbs adapted to embrace said cane when turned upon the same, foldable arms connected to the end of one of said limbs, a collapsible seat secured with its front end to said arms, a ring on said cane, to which the rear end of said seat is secured, substantially as described and for the purpose set forth.

In testimony whereof I affix my signature.

CHARLES JAQUET.
